DESIGN FOR A CALCULATING MACHINE

Frederick A. Niemann and Alfred L. Mell, Chicago, Ill., assignors to Felt & Tarrant Manufacturing Co., Chicago, Ill., a corporation of Illinois

Application August 26, 1938, Serial No. 79,574

Term of patent 14 years

To all whom it may concern:

Be it known that we, Frederick A. Niemann, and Alfred L. Mell, citizens of the United States, residing at Chicago, in the county of Cook and State of Illinois, have invented a new, original, and ornamental Design for a Calculating Machine, of which the following is a specification, reference being had to the accompanying drawings, forming a part thereof.

In the drawings,

Figure 1 is a perspective view of a calculating machine embodying our design;

Figure 2 is a side elevational view; and

Figure 3 is a rear elevational view of the machine of Fig. 1.

That side of the machine not shown in Fig. 1 is substantially identical to the side shown in Fig. 2.

We claim:

The ornamental design for a calculating machine, substantially as shown and described.

FREDERICK A. NIEMANN.
ALFRED L. MELL.
